UNITED STATES PATENT OFFICE.

FREDERIC G. NICOLAUS, OF CLEVELAND, OHIO, ASSIGNEE TO AMERICAN STOVE COMPANY, OF ST. LOUIS, MISSOURI, A CORPORATION OF NEW JERSEY.

CLOSED GAS STOVE AND VALVE THEREFOR.

Application filed January 19, 1927. Serial No. 162,143.

This invention relates to certain improvements in closed gas stoves and valves therefor, and the invention pertains to embracing within the closure burners, gas manifold and controlling valves.

I have found from actual experience that the ordinary shaped gas valve for controlling the flow of fuel, if embraced by a closure that also contains the burners they are subjected to rather a high temperature, and they have a tendency to lock tight and prevent them being operated for controlling the flow of gas.

Therefore one object of my present invention is to construct a gas valve that is short and stubby, which is enclosed in a correspondingly shaped housing, the said valve and housing and manifold being embraced in said closed structure and subjected to a relatively high temperature, whereby the said valves will never lock but can be freely moved by a handle extending slightly beyond the wall of the closed structure for controlling the flow of fuel to the burners.

Another object of the present invention is to embrace a gas manifold in a closed structure and locate the gas manifold adjacent to its wall, and attach a gas valve housing to the manifold, the wall of said closure having an elongated slot and a handle extending from the gas valve through the said wall whereby it can be freely moved vertically.

Another object of the present invention is in the specific construction of the handle and the gas valve whereby they interlock substantially in the manner shown, the handle being accessible through the wall of the structure.

A further object of the present invention is to construct that part of the handle that is attached to the gas valve with a curved outer surface, the curved outer surface passing through a slot in the wall of the closed structure and a handle attached to the curved structure intermediate its ends whereby it is adapted to be operated in the manner hereinafter described.

Further objects of the present invention will appear from the following description:

Figure 1 is a top plan view of a part of the range with the top plates removed.

Figure 2 is a perspective view of a part

of a gas stove or range, the same being closed, showing the present improvement applied thereto.

Figure 3 is a vertical section of the front portion of Figure 1, the handle having a vertical movement.

Figure 4 is a horizontal section of my improvement showing the parts arranged so that the gas valve and its handle have a horizontal movement.

Figure 5 is an enlarged sectional view similar to Figure 3, the same showing the burner and manifold communicating with the valve housing, the handle having a vertical movement.

Figure 6 is a vertical sectional view showing the parts arranged so that the handle is moved in a horizontal direction.

Figure 7 is a horizontal sectional view of Figure 6, with the parts so arranged that the handle moves in a horizontal direction.

In carrying out the present improvement a closed structure is provided with a front wall 1, an end wall 2, the rear wall (not shown) being also closed. The end wall next to the oven not shown, is also closed whereby a closed structure is provided. Located in this closed structure is a manifold 3, the said manifold extending parallel the outer wall 1, and adjacent said wall. A valve housing 4 is located within this housing and is immediately below the manifold 3, the said valve housing being also adjacent the wall 1 of the closure. This outer wall 1 is provided with vertical slots 5 as shown in Figure 2, for the purpose of enabling the curved portion 6 that is a part of the operating handle to extend outwardly through, and to permit the curved portion to be vertically oscillated. This curved portion has its inner end 7 reduced and made circular in shape to fit within a curved wall 8 that extends longitudinal the valve 9. This curved wall 8 is in that portion adjacent the wall 1 with a slot 10 into which a reduced part 11 of the curved portion 6 passes. A screw 12 passes through an opening 13 made in the circular part 7, and into the valve 9. From the foregoing it will be understood that the curved wall 8 serves to lock the curved portion 6 to the valve and to prevent it from having any independent movement. In the construction here shown the curved portion 6 has a pro-

105

jection 14 extending from its outer wall and located substantially midway between the opposite ends of the curved part 6. To this projection 14 a suitable handle 15 is attached. In the construction here shown, the handle is screw-threaded on the projection 14.

The valve 9 is provided with gas passages 16 and 17, the one 16 communicating with a 10 connection 18 that is screwed into the manifold 3 and the one 17 communicating with an adjustable nipple 19 that communicates with the shutter portion 20 of the burner manifold 21.

15 The burner 1' that is embraced in the housing 1 (the heat from the burner or burners being enclosed in the same structure with the valve housing and its valve) necessarily raises the temperature of the valve 20 and the valve housing. As stated in the first part of this specification, I have found that the ordinary elongated gas valve has a tendency to lock and does lock when it is placed inside of the closed housing. I find, 25 however, by changing the shape of the valve and its housing to that here shown, that it does not lock and that at all times it moves freely. This may be due to the fact that when the said housing and the valve become 30 expanded from heat due to the relative suddenness of the angle, that the valve is slightly forced outward against its spring 22, and thereby is prevented from becoming locked. No matter what the reason is, I find it to be 35 true that when this valve is enclosed in the said housing and subjected to the heat of the burner, it will move freely at all times and have no tendency to locking.

The curved projecting portion 6 of the 40 handle passes through the slot 5 made in the wall 1, and the slot is made of such width and the curved portion 6 of such thickness as to give the appearance of substantially closing the said slot.

45 By means of a structure such as herein described, it will be observed that a gas stove is produced in which neither the valves, the manifold nor the burners are visible, producing a gas stove having an improved appearance. It will be observed that the one part that is visible from the outside of the closed structure is the handle 15 with the small part of the curved portion which lies between the handle and the gas valve. 50 In other words I am enabled to construct a gas stove in which none of the operating parts are outside of the closed structure with the exception of the handles for controlling the gas valves 9.

55 It will be observed from the foregoing that I have disclosed constructions whereby the handle 15 may oscillate either in a vertical or a horizontal direction, while at the same time the vertical direction is the preferred construction.

Attention is directed to the fact that the valve controlling lever 23 controls the valve for the gas that is fed to a manifold 24 with its inner end connected with the oven burner 25. The manifold 26 that connects with the oven manifold 24, it will be noticed, doubles outward and then extends inward into the mouth of the manifold 24.

The manifolds 26 as shown, have their inner ends doubled on themselves and their 75 inner extremities connected with the burners 1' whereby the gas being fed to these burners is thoroughly mixed with air before the gas issues from the burners 1'.

80 Although I have described in detail the present improvement, I wish it understood that the construction may be varied without departing from the spirit of the invention so long as the variation is within a fair interpretation of the appended claims. 85

Having thus described my invention, what I desire to claim and secure by Letters Patent is:

1. A gas stove comprising a closed structure, a manifold in the closed structure extending parallel the front wall of the closure and adjacent said wall, a gas valve housing within the closure connected with the said manifold, a burner located within the said closure, the valve housing having communication with the burner, a valve in the said housing, the front wall of the closure having an elongated opening and a handle located outside of the closure and having a portion extending through the said opening, its inner end connected with the said valve, the handle having an intermediate elongated curved portion extending through the said elongated opening, the parts operating for the purpose described. 90

2. A gas stove comprising a closed structure, a manifold within the said structure and extending parallel the outer wall and adjacent thereto, a valve housing communicating with the manifold, the outer wall having a vertically elongated opening, a handle located outside of the said wall and having part thereof passing through the said elongated opening with its inner end connected with one end of the said valve, the handle intermediate its ends having a vertically elongated curved portion extending through the said vertical opening of the wall, the parts operating for the purpose described. 105

110 3. A gas stove having a closed structure, a manifold within the structure extending longitudinal its outer wall and adjacent thereto, a valve housing within the said structure and communicating with the said manifold, a valve in the said housing, a handle passing through the front wall of the closure and its inner end being enlarged, one end of the valve having a socket for receiving the enlarged end of the handle, 115

120

125

130

and means for securing the enlarged end of the handle to the valve whereby the parts operate in the manner described.

4. A gas stove comprising a closed structure, a manifold in the said structure, a valve housing communicating with the manifold and also within said structure, a valve in the said housing, one end of the valve having a projecting flange forming a socket, and

10 a handle located outside of the outer wall

of the housing and extending therethrough, its inner end enlarged and received by the said socket, the flange of the socket cut out to receive an intermediate reduced portion of the handle, the parts operating as described.

In testimony whereof I hereunto affix my signature.

FREDERIC G. NICOLAUS.
